UNITED STATES PATENT OFFICE

JOHN P. PEARSON, OF LA PORTE, INDIANA, ASSIGNOR TO METAL DOOR & TRIM CO., OF LA PORTE, INDIANA

METALLIC DOOR STRUCTURE OR THE LIKE

Application filed December 1, 1926. Serial No. 151,870.

The invention relates to metallic doors or the like, and has for its object to provide a device of this character comprising rails and stiles and a panel, which panel is disposed in a channelled member, and which channelled member is provided with an auxiliary channel, into which flanges of the rails and stiles extend for holding said channelled member and the panel carried thereby.

10 A further object is to provide a metallic door or the like, which door is formed from rails and stiles and a panel with a molding, which molding is provided with a channel in which is disposed the edges of the panel, and 15 with an auxiliary channel into which diverging flanges carried by the rails and stiles extend for holding said molding and the panel carried thereby against lateral displacement.

A further object is to provide the molding 20 with a removable side, whereby upon removal of the side a panel may be easily and quickly removed or placed in position. Also to provide securing means for holding said removable portion in position.

25 A further object is to form the rails and stiles from sheet metal bent to angular form in cross section, thereby forming opposite sides terminating in inwardly extending flanges and the adjacent ends or edges of the 30 inwardly extending flanges with outwardly extending flanges preferably diverging and disposed in a channel of the molding.

With the above and other objects in view the invention resides in the combination and 35 arrangement of parts as hereinafter set forth, shown in the drawing, described and claimed, it being understood that changes in the precise embodiment of the invention may be made within the scope of what is claimed without 40 departing from the spirit of the invention.

In the drawing:

Figure 1 is a view in elevation of the door.

Figure 2 is a vertical transverse sectional view through the door taken on line 2—2 of 45 Figure 1.

Figure 3 is a perspective view of the removable section of the molding.

Figure 4 is a detail perspective view of the fixed portion of the molding.

50 Figure 5 is a vertical transverse sectional

view through another form of molding and door.

Referring to the drawing, the numeral 1 designates the stiles of the door, 2 the top rail and 3 the bottom rail thereof. The stiles and rails are preferably formed from single sheets of material bent to rectangular form as shown in Figure 2, with their flanges 4 extending inwardly towards each other. The inner edges of the flanges 4 terminate in 60 outwardly diverging flanges 5, the purpose of which will presently appear. The door is provided with a panel 6, preferably formed of glass as shown in Figure 2, and disposed within the door and extending around the 65 panel 6 is a molding 7, which molding receives therein at 8 the marginal edge of the panel and is provided with a channelled member 9 having converging flanges 10, which receive therein the diverging flanges 5 of the 70 rails and stiles as clearly shown in Figure 2, thereby securely anchoring the molding to the rails and stiles, and the assembly of the door may be an endwise one, after which 75 the molding may be secured together in any suitable manner, for instance by spot welding at their abutting ends, and the securing of the stiles and rails may be accomplished in the same manner. The molding 7 is provided with removable sides 11 having flanges 80 12 which engage the outer side of the glass panel 6, and extending through the removable sides 11, and through the adjacent flange 4 of the stile or rail are securing screws 13, which thread through the flange 4, and when 85 in position draw the removable sides of the molding into close binding engagement with the panel 6. It will be noted that the molding as a whole is substantially a molding having a main channel for the reception of 90 the panel edge and an auxiliary channel for the reception of the flanges 10. Consequently a molding is provided which is simple in construction, and when the diverging flanges 5 are in the auxiliary channel of the channelled member 9, a rigid structure is provided. By providing the removable sides 11 for the molding, it will be seen that the panel may be easily placed in position or removed, 95 which is particularly desirable where a glass 100

panel is used, which often requires replacement incident to breakage.

Referring to Figure 5 wherein another form of the device is shown, the molding 7^a is formed from a single piece of material bent to form the panel receiving channel 14 for receiving the panel 15, which panel 15 may be of any kind. However the molding structure is particularly adapted for a panel other than a glass one. In the molding 7^a in Figure 5, the flanges 10^a of the rails and stiles extend into the auxiliary channel 16, in the same manner as shown in Figure 2, however in this 15 form the flange 12^a, which engages the side of the panel 15 extends downwardly and is formed integral with the channel member 9^a. Consequently a complete integral double channel molding is provided. By providing the diverging flanges 5, which may have a slight spring action, it is obvious a binding engagement thereof will take place within the auxiliary channel which will prevent any play, and at the same time the walls of the stiles and rails will be prevented from spreading and any special securing means for preventing the spreading of said walls is obviated, thereby reducing the cost of manufacture to a minimum.

From the above it will be seen that a door is provided with a panel holding molding, which may be easily and quickly assembled on a door for holding a panel, and where a glass panel is used the molding may be easily and quickly removed, that is one side thereof for replacing the panel in case of damage thereto. It will also be seen that special securing means is reduced to a minimum, and the parts interlock and cooperate with each other when assembled to form a rigid structure. Although the invention has been described in connection with a metallic door, it is to be understood that the same may be applied to various analogous structures, for instance panelling generally.

The invention having been set forth what is claimed as new and useful is:—

1. The combination with a device of the character described comprising side members, end members and a panel, of a molding, said molding having a main channel in which the edges of the panel are disposed and a single auxiliary channel, engaging flanges carried by the side and end members and disposed in the auxiliary channel.

2. The combination with a device of the character described comprising side members, end members and a panel between said members, of a molding engaging said members, a channel carried by said molding and in which the adjacent edges of the panel are disposed, diverging flanges carried by the side members and end members, an auxiliary channel carried by said molding, said diverging members being disposed in the auxiliary channel.

3. A metallic door comprising stiles, top

and bottom rails, a panel, a molding engaging the inner sides of the stiles and rails, a main channel carried by said molding and in which the edges of the panel are disposed, an auxiliary channel carried by said molding, the opposite walls of said auxiliary channel converging towards the rails and stiles, and inwardly diverging flanges carried by the rails and stiles and disposed in the auxiliary channel.

4. A metallic door comprising stiles and rails, said stiles and rails on their inner sides being provided with flanges extending towards each other, diverging engaging flanges carried by the last named flanges, a panel, a molding, a main channel in said molding and in which the edges of the panel are disposed and an auxiliary channel in said molding in which the diverging engaging flanges are disposed.

5. The combination with a door member, a panel edge adjacent said member, of means for attaching said panel to the door member, said means comprising a molding, a main channel carried by the molding and in which the panel edge is disposed, a wedge shaped auxiliary channel carried by the molding, diverging flanges carried by the door member and disposed in the wedge shaped auxiliary channel, said door member and diverging flanges being formed from a single piece of sheet material bent to form.

6. A panel holding structure for attaching a panel to a member disposed adjacent the same, said holding structure comprising a molding engaging one side of the panel, a channeled member carried by said molding substantially within the plane of the panel, a member carried by the member adjacent the panel and disposed in the channel, said channel terminating spaced from the member adjacent the panel, a removable molding section engaging the other side of the panel and securing means carried by the removable molding and extending angularly into the member adjacent the panel.

7. A metallic door comprising stiles and rails, a panel between said stiles and rails in spaced relation thereto, a molding, a channel carried by said molding and in which the adjacent edges of the panel are disposed, an auxiliary channel carried by said molding in reversed relation to the first mentioned channel, flanges carried by the stiles and rails and extending into the auxiliary channel, and outwardly diverging walls carried by the molding and engaging the adjacent surfaces of the stiles and rails at opposite sides of the auxiliary channel.

8. A metallic door comprising stiles and rails, said stiles and rails being formed from single pieces of sheet metal bent to form, the ends of said sheet of material terminating in diverging flanges at the inner sides of the stiles and rails, a panel between the stiles and

rails, a molding carried by said panel and having a channel therein in which the diverging flanges are disposed, said diverging flanges being formed from the same sheet of material and integral with the stiles and
5 rails.

In testimony whereof I affix my signature.
JOHN P. PEARSON.
